UNITED STATES PATENT OFFICE.

HENRY CLINTON HICKS, OF MINNEAPOLIS, MINNESOTA.

STOCK-CAR.

SPECIFICATION forming part of Letters Patent No. 288,335, dated November 13, 1883.

Application filed August 16, 1883. (No model.)

To all whom it may concern:

Be it known that I, HENRY CLINTON HICKS, a citizen of the United States, and a resident of Minneapolis, in the county of Hennepin, in the State of Minnesota, have invented certain new and useful Improvements in Stock-Cars, of which the following specification is a full, clear, and exact description, reference being also had to the accompanying drawings, in

10 which—

Figure 1 is a cross-sectional view of a car, showing my improvements arranged therein. Fig. 2 is a detail of one of the feed-racks and watering-troughs folded up; Figs. 3, 4, and 5, 15 details of a portion of one of the division-bars. Fig. 6 is a sectional side elevation of the car, as shown in Fig. 1. Fig. 7 is a perspective view of one of the feed-racks detached. Fig. 8 is a cross-section of a portion of the car, showing the manner of arranging the chains and guard-plates.

In the drawings, A is the floor, and B the stanchions or open frame-work of a stock-car.

C' C² are two upright L or corner iron bars, 25 connected to each other at their tops and bottoms by parallel horizontal cross-bars a' a², and having upright slats a³ parallel with the corner-bars connecting the cross-bars, as shown in Fig. 7.

30 b is a cross bar or brace connecting the slats and corner-bars centrally, all these parts being of metal and firmly riveted together, and forming the front of the feed-rack.

D' D² are two flat bars, pivoted at one end to 35 one of the stanchions B, and by their other ends to the upper and lower ends of the corner-iron C', while a similar bar, D³, is likewise pivoted to the lower end of the corner-iron C'.

Attached to one of the cross-slats of the frame 40 of the car, on a line level with the upper cross-bar, a', and pivoted bar D', is a "yoke-shaped" bar, E, to whose inner ends are pivoted by one end two bars, D⁴ D⁵, (similar to the bars D' D² D³,) and pivoted by their other ends to the cross-bar a' and upper end of the corner-iron C', as shown in Fig. 7.

The pivots by which the bars D' D² D³ D⁴ D⁵ are secured to the stanchions B and yoke E', are all in line with each other, and the pivots 50 by which the same bars are connected to the corner-irons C' C² and cross-bar a' are in line with each other, so that the whole device may

be folded back between the stanchions without cramping any of the parts.

The outer ends of the bars a' a² project beyond the corner-irons C' C², so that when the rack is folded up, as shown in Fig. 2, these projecting ends rest against the stanchions B and prevent the rack being pressed in too far, and also prevent any pressure from the animals or other causes from injuring the racks. Small points t will be formed upon the bottoms of the corner-irons C' C², to enter the floor of the car when the racks are open and assist in holding the rack.

Secured to the frame of the car at any suitable point, so as not to project inside the stanchions, is a water reservoir or tank, G, having a pipe, c, leading into a small watering-trough, H, adapted to fit in between the bars D⁴ D⁵ and 65 U-shaped bar E, the trough being arranged to swing upon the pipe c as a pivot, while another pivot, d, is set into the stanchion B, to support the opposite side of the trough.

D⁶ is a small loop or strap attached to the 70 bars D⁴ D⁵, upon which the free end of the pivoted trough rests. By this arrangement the watering-trough H may be turned down, as shown in Fig. 1, or turned up, as shown in Fig. 2, without interfering with the pipe c, 75 which supplies water to it, as the pipe itself is one of the pivots upon which the trough swings.

The trough H may be supplied with a cover, if desired. The outer end, e, of the trough is 80 made flaring outward toward the top, so that when turned up, as shown in Fig. 2, the water in the trough and the tank will all run out, so that no danger exists of impure water accumulating in the trough or tank in 85 warm weather or water freezing in them in cold weather. The troughs H will be large enough to hold the necessary amount of water to satisfy an animal at one drinking, and the tanks G may be made large enough to hold sufficient to supply the troughs several 90 times, as at G', or only once, as preferred. When the tanks G are made large, each of the pipes c will be provided with a stop-cock, g, (see Fig. 6,) so that when the troughs H are 95 full the water may be shut off to avoid waste. The large tanks will only be used in warm weather, usually. One long tank may be arranged upon the top of the car, with pipes 100

leading to each of the several troughs H, and with stop-cocks in each pipe to regulate the supply. The pipes c may be arranged with a valve adapted to be closed by the upward 5 tilting of the tanks and opened by turning them down again, if desired. These folding feed racks and troughs may be all arranged upon one side of the car, or upon both sides of the car, or alternately upon both sides, as preferred. They are generally intended to be used 10 in connection with that class of stock-cars in which the animals are divided by movable and adjustable partitions into separate stalls. By these simple arrangements the feeding appliances 15 may be folded back entirely out of the way, so that when used on cars the latter may be used for freight or other purposes equally as well as if the racks were not in the cars.

The stanchions will be arranged in pairs, as 20 shown, with one of the feed-racks between each pair of stanchions, and across the upper part of the car above the spaces between each opposite pair of the stanchions are journaled 25 shafts F', having chain-pulleys h' upon their ends above and in line with similar chain-pulleys, h², attached to or near the floor of the car, between each pair of the stanchions. h³ 30 are a series of similar chain-pulleys attached to the car near the roof and in line with the pulleys h', while still another set of chain-pulleys, h⁴, are attached to the car beneath and a little in the rear of the pulleys h', so that endless chains K may be arranged upon each 35 set of the pulleys, as shown.

M are flat wooden bars having steel rods i' embedded within their upper and lower edges, and secured to the bars by straps i², the ends 40 of the rods extending beyond the bars M, and provided with eyes or other means of securing them to the chains K at regular intervals, as shown.

Each of the shafts F' will be provided on one or both ends outside of the car with a hand-wheel, F², or other means for revolving 45 it, so that by revolving the shaft the bars M may be run down to form divisions or stalls across the car for the stock, or run up close to the roof out of the way when not in use.

Sheet-metal guards P will be arranged to 50 cover the inner faces of each pair of the stanchions B, leaving a narrow slit for the passage of the bars M. These guards not only protect the chains from injury by the animals, but also prevent injury from freight when the 55 cars are used to transport goods. Furthermore, the guards P support the bars M at their ends and greatly stiffen and strengthen them.

m in Fig. 6 represents a small dog or pawl 60 adapted to catch upon one of the links of the chain K, when the bars M are lowered down, to hold them down and prevent them being raised accidentally or by the action of the animals. One of these catches will be arranged for each of the chains K. 65

Having described my invention and set forth its merits, what I claim is—

1. The combination of corner-irons C' C², cross-bars a' a², slats a³, pivoted bars D' D² D³ D⁴, stanchions B B, or their equivalent, and 70 means for connecting said pivoted bars to the body or frame of a car or other place when animals are to be fed, substantially as and for the purpose set forth.

2. The combination of the stanchions or 75 similar devices, B, corner-irons C' C², bars D' D² D³ D⁴ D⁵, and yoke E, substantially as shown.

3. The combination of the stanchions or 80 similar devices, B, corner-irons C' C², bars D' D² D³ D⁴ D⁵, yoke E, strap D⁶, and pivoted watering-trough H, substantially as described.

4. The combination of a stationary tank, G, discharge-pipe c, and trough H, pivoted on the 85 said discharge-pipe, substantially as and for the purpose herein specified.

5. The combination of the stanchions B, corner-irons C' C², cross-bars a' a², having projecting ends, stanchions B B, and pivoted bars D' D² D³ D⁴, substantially as specified. 90

6. In a stock-car, the combination of the stanchions B, arranged in pairs, guards P, bars M, and means for raising and lowering said bars, substantially as described.

7. The combination, in a stock-car, of a folding feed - rack, a stationary water - tank, a swinging watering-trough connected with the water-tank by a pipe on which the trough also turns as a pivot, and a set of partition-bars, M, adapted to be raised and lowered, substantially as and for the purpose herein specified. 100

8. In a stock-car, the endless chains K, bars M, having rods i and straps i², and means for connecting said bars to said chains, substantially as and for the purpose specified. 105

9. In a stock-car, the combination of a series of endless chains, K, arranged substantially as described, bars M, and catches m, as and for the purpose set forth.

In testimony whereof I have hereunto set 110 my hand in presence of two subscribing witnesses.

HENRY CLINTON HICKS.
